SHAVER OR SIMILAR ARTICLE

Seymour Rappoport, New York, N. Y., assignor to Ron-
son Electric Shaver Corporation, Stamford, Conn., a
corporation of Connecticut

Application April 12, 1956, Serial No. 41,037

Term of patent 14 years

(Cl. D22—3)

Fig. 1 is a front elevation of a shaver embodying my new design;

Figs. 2, 3, and 4 are respectively a side elevation, top plan view, and rear perspective view of such shaver.

I claim:

The ornamental design for a shaver or similar article, substantially as shown.
